(57) **CLAIM**

The ornamental design for an eyeglass frame, as shown.

DESCRIPTION

FIG. 1 is a top, front, right-side perspective view of a first embodiment configured as in use;

FIG. 2 is a front elevational view of same;

FIG. 3 is a top plan view of same;

FIG. 4 is a right-side elevational view of same, the left side view being a mirror image thereof;

FIG. 5 is a rear elevational view of same; and,

FIG. 6 is a bottom plan view of same.

The broken lines shown in FIGS. 1-6 are for illustrative purposes only and form no part of the claimed design.
